US00D888649S

(12) United States Design Patent (10) Patent No.: US D888,649 S
(45) Date of Patent: * Jun. 30, 2020

(54) TIRE CARRIER

(71) Applicant: OMIX-ADA, INC., Ann Arbor, MI (US)

(72) Inventors: Patrick W. Bennett, Gainesville, GA (US); Jesse T. Neal, Atlanta, GA (US)

(73) Assignee: OMIX-ADA, INC., Ann Arbor, MI (US)

() Term: 15 Years

(21) Appl. No.: 29/649,426

(22) Filed: May 30, 2018

(51) LOC (12) Cl. 12-16

(52) U.S. Cl.

USPC D12/412

(57) CLAIM

The ornamental design for a tire carrier, as shown and described.

DESCRIPTION

FIG. 1 is a perspective view of a tire carrier showing our new design.

FIG. 2 is a front elevational view thereof.

FIG. 3 rear elevational view thereof.

FIG. 4 is a top plan view thereof, the bottom plan view is a mirror image of the top plan view.

FIG. 5 is a right side elevational view thereof; and,

FIG. 6 is a left side elevational view thereof.

The broken lines depict portions of the tire carrier that form no part of the claimed design.

1 Claim, 5 Drawing Sheets
